INKSTAND SET

Frank M. Ashley, Brooklyn, N. Y.

Application January 17, 1935; Serial No. 2,233

9 Claims. (Cl. 120—4)

My invention relates to inkstands and desk sets.

The object of my invention is to provide an inkstand of simple construction capable of holding a considerable quantity of ink, practically all of which may be ultimately taken up by the pen.

A further object is to provide an inkstand designed and proportioned to support a penholder carrying a pen, the penholder serving as a cork for the stand and held in the dip thereof either vertically or at an angle to the vertical axis of the stand.

A further object is to provide an inkstand in which the depth of the well, measured from the lower end of the penholder is such that the pen will extend practically to the bottom of the well without touching the same, whether resting vertically or at an angle to the vertical axis.

A further object is to provide a desk set comprising an inkstand, and a penholder which serves as a closure for the well when resting in the dip regardless of the angle at which it is supported.

A further object is to construct the dip and lower end of the penholder in such a form relatively, that the penholder will be supported in such a manner as to prevent it from contacting the sides of the dip and becoming smudged with ink on the gripping surface.

Referring to the drawing which forms a part 30 of this specification:

Fig. 1 is a vertical sectional view thru an inkwell shown with a pen supported therein, illustrating my invention.

Fig. 2 is a plan view of the inkwell illustrated 35 in Fig. 1.

Fig. 3 is a vertical sectional view of another form of stand in which my invention is embodied.

Fig. 4 is a plan view of the cover shown in section in Fig. 3.

Fig. 5 is an inverted plan view of the cover construction shown in Fig. 3.

10 indicates the body portion of an inkstand which is illustrated as made of glass, but which may be made of any suitable material.

11 indicates an inkwell and 12 the cover portion of the inkstand.

13 indicates a thin top-plate which fits over the cover to mask it and to provide an ornamental top that may be made of the same material as 50 that which is used in making the penholder, thus matching to present a set appearance.

The cover may be made of molded bakelite or hard rubber, but I prefer to make it of stiff soft rubber which serves more perfectly in forming 55 an air-tight joint between the cover and glass,

and between the penholder and cover when the penholder is not made with a soft lower end such as rubber or cork.

The cover is preferably formed with a depending flange 14 which fits tightly in the top of the well at 15, and carries a conical dip tube 16, which is preferably formed integral as illustrated, the inner diameter at its lowest end being about three eighths of an inch, and the diameter at the point where the penholder rests in contact therewith being seven sixteenths of an inch approximately, thus serving to support the penholder, the lower end of which rests therein and is formed at its lower end to present a spherical surface at its outer sides so that the closure is complete whether the penholder is resting in a vertical or inclined position.

The distance from the lower end of the penholder to the bottom of the well when at rest should be about one inch.

The angle at which the pen may rest is governed by the length of the dip below the point at which the penholder rests, the shank of the pen abutting the dip at 17 to prevent contact of the penholder with the dip at 18, thus preventing the penholder from becoming smudged with ink, as will be readily understood.

By making the dip shallow in depth, very little dust is collected, and the penholder is easily inserted therein.

By forming the bottom of the well as illustrated, the pen point may swing from its vertical to an inclined position without danger of striking the bottom of the well, and by using a feed-plug 19, practically all of the ink can be obtained for writing.

In Figs. 3 and 4, I have shown a stand formed to provide an inclined top, the body portion being formed with two of its side walls inclined as illustrated, and the bottom of the well is provided with a partition 20, the construction being such that ink trapped in one side of the stand in chamber 21, may be caused to flow into chamber 22 by tilting the stand.

The construction shown in Figs. 3 and 4, also permits the penholder to incline further from the vertical position than in that shown in Fig. 1, due to its initial inclination, and the dip is more clearly seen in the act of inserting the pen therein.

By using a stainless steel pen and a hard rubber feed-plug, held in a pen holder such as illustrated, in combination with an inkstand made of glass provided with a rubber cover, a very simple and durable set may be provided at a low cost.

55

Having thus described my invention, I claim as new:

- 5 1. A desk set comprising an inkstand and a pen holder, said inkstand comprising a body portion having a chamber for ink formed therein, a cover for said chamber having a shallow open funnel-shaped dip decreasing in diameter from its upper to its lower end and designed to support a pen holder the lower end of which is formed to rest in and close said dip, and a pen holder carrying a pen the point of which is supported above the bottom of said chamber adjacent thereto, and its shank resting in contact with the lower end of the dip and serving to entirely support the penholder in an inclined position and from contact with the side wall of the dip.
- 10 2. An inkstand set comprising a body portion having a chamber formed therein the bottom of which is formed with a shallow saucer shaped depression, a cover for said chamber having a shallow funnel shaped dip adapted to support a pen holder, a closure for said dip consisting of a pen holder the lower end of which is formed spherical to serve as a closure while holding a pen in said depression and at an angle to the vertical axis thru the body portion, and a pen carried by the holder the shank of which normally rests against the dip to entirely support the penholder in its inclined position.
- 15 3. As stated in claim 2, plus; said cover being made of elastic material such as soft vulcanized rubber.
- 20 4. An inkstand comprising a body portion having a chamber for ink formed therein, said body portion formed with thickened side walls comprising an outer flat inclined wall of greater height than the opposite wall, and a cover for said chamber supported in an inclined position on the body, said cover having a shallow dip formed to support a pen holder, and located eccentric in the cover.
- 25 5. As stated in claim 4, plus; and a pen holder supported in and closing said dip, and movable to different positions without opening it.
- 30 6. An inkstand comprising a body portion hav-

ing a chamber for ink formed therein, a cover for said chamber made of elastic material such as soft vulcanized rubber and formed to provide a depending funnel-shaped dip, and a top-plate of non-absorbent plastic material formed to overlie and embrace the cover and held in position thereby. 5

7. An inkstand set comprising a body portion having a well formed therein, a cover formed with a shallow dip of conical form at its lower end, a pen-holder having a spherical surface resting in contact with the dip tube just above its lower end and a pen, the shank of which rests against the lower edge of the tube and serves as the sole means for supporting the pen in an inclined position relative to a vertical line without contacting the tube above its point of support; the construction being such that the penholder serves as a cork for the inkstand, and may be supported in different positions relative to a fixed 15 position of the body portion.

8. An inkstand comprising a body portion having a chamber for ink formed therein, a soft rubber cover for said chamber having a dip designed to support a pen holder, and a top plate of non-absorbent material overlying the cover in close contact therewith and held in position thereby, to protect the rubber from becoming stained by the ink and to provide an ornamental appearance. 20

9. An inkstand set comprising a body portion 30 having a well for ink formed therein and a cover portion formed to provide a shallow dip-tube, and a pen-holder having a spherical lower end resting in contact with the wall of the dip-tube just above its lower end and carrying a pen the shank 35 of which rests against the lower end of the dip-tube and supports the pen-holder in an inclined position without contact with the tube above the point of support; the construction being such that the pen-holder serves as a closure for the well 40 and that the pen-holder may be moved to different positions of rest without moving the body portion.
